GRANT HAMMOND, OF HARTFORD, CONNECTICUT, ASSIGNOR OF ONE-THIRD TO ALVA C. WASHBURN, OF PITTSFIELD, MASSACHUSETTS, AND ONE-THIRD TO FREDERICK G. CRANE, OF DALTON, MASSACHUSETTS.

FIREARM.

1,140,513.

Specification of Letters Patent. Patented May 25, 1915.

Application filed June 9, 1914. Serial No. 843,992.

To all whom it may concern:

Be it known that I, GRANT HAMMOND, a citizen of the United States, residing at Hartford, in the county of Hartford and State of Connecticut, have invented a new and Improved Firearm, of which the following is a specification.

My invention relates more especially to that class of firearms in which the operations of loading, ejecting of shells, and so forth, are performed automatically, and an object of my invention, among others, is to provide a firearm of this class that shall be simple in construction and particularly efficient in operation.

One form of firearm embodying my invention and in the construction and use of which the objects herein set out, as well as others, may be attained, is illustrated in the accompanying drawings, in which—

Figure 1 is a view in side elevation of a firearm embodying my invention, with parts broken away to show construction. Fig. 2 is a top plan view, with parts broken away to show construction. Fig. 3 is a top plan view of the back part of the firearm with the locking bolt support removed. Fig. 4 is a detail view showing the construction of the locking bolt and its actuator, the parts being disconnected. Fig. 5 is a detail side view of the locking bolt support. Fig. 6 is a detail view, partially in section, showing the arrangement of the breech bolt actuating lever, the breech bolt and firing pin sleeve, the latter being unlocked from the breech bolt. Fig. 7 is a like view, omitting the breech bolt actuating lever, the breech bolt being shown in full and in locked engagement with the firing pin sleeve.

In the accompanying drawings the numeral 6 indicates the handle, 7 the trigger guard, 8 the trigger, 9 the hammer, 10 the barrel and 11 the receiver, a portion of which composes the frame of my improved firearm, that as to such parts, may be of any preferred form of construction.

My invention pertains especially to means for locking the slide with the breech-bolt, and detailed description of the construction and operation of other parts is therefore omitted, as will be understood from the following general description.

Briefly stated, the forward part 12 of the case is moved forward by the force of the

gases of explosion, carrying with it the rear part 13, the two parts being secured together, and a spring 14 is employed for moving the case in the opposite direction or backward. In this operation the gases expand into an expanding chamber 46 between a tube 47 and a sleeve 48 upon which sleeve the forward part 12 of the case has a sliding fit. The sleeve 48 is secured to the end of the barrel 10 as by means of interengaging screw threads, and the tube 47 is secured as by means of interengaging screw threads within the end of the forward part 12 of the case, holes 49 in the end of the tube being provided to receive a spanner wrench by means of which said tube 70 may be removed. A breech-bolt 15 is rotatably and longitudinally movable in the receiver 11, this breech-bolt having a cam groove 16 that receives the inner end of a breech-bolt locking bolt 17, movably mounted in a locking bolt support 18 pivotally attached to a lug 19 projecting from the surface of the rear part 13 of the case.

A firing pin sleeve 37 containing a firing pin and having a head 31 is located in the breech-bolt, a latch 38 on the head engaging a notch 45 in the end of the breech-bolt to hold the bolt and firing pin sleeve at times against relative turning movement under the influence of a spring 39. In assembling the parts, the firing pin sleeve is inserted within the breech-bolt, a lug on said sleeve passing through a groove formed lengthwise on the inner surface of the breech-bolt and into registry with an annular groove on the inner surface of the breech-bolt. Relative rotating movement is now given to the firing pin sleeve and breech-bolt in opposition to said spring until the latch 38 engages the notch 45 in the end of the bolt to hold the sleeve and bolt from relative turning movement, as shown in Fig. 7 of the drawings, this movement having passed the lug on the firing pin sleeve into the annular groove in the wall of the breech-bolt to hold the two parts from relative longitudinal movement. The lug 40 containing the latch on the firing pin sleeve is now in line with one of the lugs 33 on the breech-bolt. The breech-bolt is inserted in the receiver 11, the lugs 33 passing into longitudinal grooves in the inner wall of the receiver, the lug 40 passing into one of said grooves, to an ex-

tent to cause the lugs 33 to register with an annular groove on the inner wall of the receiver, the lug 40 on the head of the firing pin sleeve remaining in said longitudinal groove. At this point the latch 38 engages the end of the receiver, unlocking the breech-bolt, which is caused to turn by the spring 39, passing the lugs 33 into the annular groove in the wall of the receiver and locking the breech-bolt therein, the relative positions of the breech-bolt and firing pin sleeve at this time being shown in Fig. 6 of the drawings.

The support 18 has an opening extending transversely to the locking bolt 17 to receive a locking bolt actuator 21 that also extends through an opening 20 in the locking bolt. The lower end of the locking bolt has a projection 22 formed to engage a hole 23 in the cam groove 16 in the breech-bolt. The actuator has a locking cam surface 24 and an unlocking cam surface 25 to engage the edges of the opening 20 to move the locking bolt into locked or unlocked position with respect to the breech-bolt. The actuator has holders 26-27 which are projections having straight ends terminating the cam surfaces, these straight ends being adapted to be located substantially in line with the inner edges of the opening 20 so that when engaged with the walls of said opening they will offer positive resistance to movement of said bolt into the opening 23 at certain times, or out of said opening at other times. A spring pressed plunger 28 is located in a recess in the lug 19, the end of this plunger engaging a shoulder on the support to hold the latter in its normal position with the locking bolt placed to effect its function. The bolt projects through a slot 29 in an extractor 30 attached to the head 31 of the firing pin sleeve, upon which the breech-bolt is partially supported.

In the operation of the firearm the case composed of the parts 12 and 13 is carried forward by the force caused by the gases of explosion and against the tension of the spring 14, carrying with it the locking bolt support 18 and breech-bolt locking bolt 17, and the latter, moving in the cam groove 16, and, acting against the cam 32, rotates the breech-bolt to its unlocked position, whereby the lugs 33 on the breech-bolt will register with the longitudinal grooves in the receiver so that the breech-bolt may be moved rearwardly. In this movement of the case, the locking bolt support and the locking bolt, the bolt actuator 21 is carried against the end wall 34 of the opening in the receiver, this pushing the actuator backward and causing the cam 24 to act upon the lower edge of the opening 20 in the locking bolt and move it downward, and the projection 22 into the hole 23. The straight surface on the end of the holder 26 on the

actuator 21 is thus caused to engage with the opening through the locking bolt and hold it against unlocking movement. As the parts thus described are promptly moved backward under the influence of the spring 14, as they reach the backward limit of their play, the rear end of the actuator 21 strikes the back wall 35 of the opening in the receiver, which causes the actuator to be moved forward, and the unlocking cam 25 engaging the upper wall of the opening 20 moves the locking bolt out of locked engagement with the breech-bolt, and the flat part on the end of the holder 27 on the actuator 21 is engaged with the upper wall of the opening 20 thus directly opposing movement of the locking bolt in its support until the actuator is directly moved from this position. When the locking bolt is thus disengaged, the lever 36 pressing against a lug 42 of the breech-bolt will be actuated, as by a spring 41 to move the breech-bolt forward, and the latch 38 engaging the end of the receiver is disengaged from the notch 45 in the end of the breech bolt and the latter is rotated to its locked position in the manner hereinbefore described. By moving the plunger 28 backwardly the locking bolt support 18 may be swung on its pivot to remove the locking bolt from the cam groove 16 and thus permit the breech-bolt to be taken out of the firearm when desired.

While I have shown and described herein a preferred construction of mechanism for accomplishing my purpose, this may be departed from to a greater or lesser degree and yet be within the spirit and intent of the invention.

I claim—

1. A firearm including a frame, a case movably mounted thereon, a longitudinally movable breech-bolt, a locking bolt mounted on the case, means for locking the locking bolt with and for unlocking it from the breech-bolt, means for positively holding the locking bolt in locked engagement with the breech-bolt, means for moving the breech-bolt to a closed position, and means for locking it in its closed position.

2. A firearm including a frame, a case movably mounted thereon, a longitudinally movable breech-bolt, a locking bolt support carried by the case, a locking bolt movably mounted on said support, means for locking the locking bolt with and for unlocking it from the breech-bolt, means for positively holding the locking bolt in engagement with the breech-bolt, means for moving the breech-bolt to closed position, and means for locking it in its closed position.

3. A firearm including a frame, a case movably mounted upon the frame, a longitudinally movable breech-bolt having a cam groove, a locking bolt carried by the case and projecting into said cam groove, means for

locking the locking bolt with and for unlocking it from the breech-bolt, means for moving the breech-bolt to closed position, and means for locking it in this position.

4. A firearm including a frame, a case movably mounted on the frame, a longitudinally movable breech-bolt having a cam groove and a hole in said groove, a locking bolt carried by the case, means for engaging the locking bolt within said hole and for disengaging it therefrom, means for moving the breech-bolt to closed position, and means for holding it in this position.

5. A firearm including a frame, a case 5 movably mounted on the frame, a longitudinally movable breech-bolt having a cam groove, a locking bolt carried by the case and with its end located in said groove, means for locking the locking bolt with and 0 for unlocking it from the breech-bolt, means for positively holding the locking bolt in locked engagement with the breech-bolt, means for moving the breech-bolt to closed position, and means for locking it in this 5 position.

6. A firearm including a frame, a case 10 movably mounted on the frame, a longitudinally movable breech-bolt having a cam groove, a locking bolt mounted on the case, an actuator extending through the locking bolt, means for moving the actuator to operate the locking bolt to engage it with the breech-bolt, means for moving the breech-bolt to closed position, and means for locking 15 it in this position.

7. A firearm including a frame, a case 10 movably mounted on the frame, a longitudinally movable breech-bolt having a cam groove with a hole in the bottom of said 15 groove, a locking bolt carried by the case, an actuator projecting through the locking bolt in position to engage an end wall of an opening in the frame to move the locking bolt into engagement with said hole, means 20 for disengaging the locking bolt from said hole, means for moving the breech-bolt to closed position, and means for locking it in this position.

8. A firearm including a frame, a case 20 movably mounted on the frame, a longitudinally movable breech-bolt having a cam groove with a hole in the bottom of said 25 groove, a locking bolt carried by the case, an actuator projecting through the locking bolt in position to engage the end walls of the openings in the frame to move the locking bolt into engagement with and to disengage it from said hole, means for moving the breech-bolt to closed position, and means 30 for locking it in this position.

9. A firearm including a frame, a longitudinally movable breech-bolt mounted in the frame, a movable support for a locking bolt, means for moving the support, the 35 locking bolt carried by said support, means

for moving the locking bolt into locked engagement with the breech-bolt, means for holding it positively in locked engagement therewith, means for unlocking it from the breech-bolt, means for moving the breech- 70 bolt to closed position, and means for locking it in this position.

10. A firearm including a frame, a longitudinally movable breech-bolt rotatably mounted in the frame and having a cam 75 groove, a movable support for a locking bolt, a locking bolt mounted in said support and projecting into said groove, means for moving the support, means for moving the locking bolt into locked engagement 80 with the breech-bolt, means for positively holding the locking bolt in locked engagement with the breech-bolt, means for unlocking the locking bolt from the breech-bolt, means for moving the breech-bolt to 85 closed position, and means for locking it in this position.

11. A firearm including a frame, a case 90 movably mounted on the frame, a longitudinally movable breech-bolt mounted in the frame, a locking bolt support carried by the case, a locking bolt mounted in said support and having an opening, an actuator projecting through said opening, said actuator 95 having a cam surface to actuate the locking bolt, means to engage the actuator to operate it, means for moving the breech-bolt to closed position, and means for locking it in this position.

12. A firearm including a frame, a case 100 movably mounted on the frame, a longitudinally movable breech-bolt mounted in the frame, a locking bolt support carried by the case, a locking bolt mounted in said support and having an opening, an actuator 105 projecting through said opening and having a cam surface to engage the locking bolt to operate it, a locking surface to positively hold the locking bolt against movement, means for operating the actuator, means for 110 moving the breech-bolt to closed position, and means for locking it in this position.

13. A firearm including a frame, a case 115 movably mounted on the frame, a locking bolt support carried by the case, a longitudinally movable breech-bolt mounted in the frame, a locking bolt mounted in said support and having an opening, an actuator 120 movable laterally of the locking bolt and having a cam surface to move the latter, the frame having a part located in the path of movement of the actuator, means for moving the breech-bolt to closed position, and means for locking it in this position.

14. A firearm including a frame, a case 125 movably mounted on the frame, a longitudinally movable breech-bolt mounted in the frame, a support mounted on the case, a locking bolt projecting through an opening 130 in the support to engage the breech-bolt, an

- actuator located in said support and projecting through the locking bolt and having a cam to move the locking bolt, said actuator being located in an opening in the support 5 to engage the end wall of the frame, means for moving the breech-bolt to closed position, and means for locking it in this position.
15. A firearm including a frame, a case 10 movably mounted on the frame, a longitudinally movable breech-bolt located in the frame, a locking bolt support pivotally

mounted on the case, a locking bolt mounted in said support, an actuator mounted in said support and extending through the locking bolt, means for moving the actuator to lock the locking bolt to the breech-bolt, means for unlocking said parts, means for moving the breech-bolt to closed position, and means for locking it in this position.

GRANT HAMMOND.
